UNITED STATES PATENT OFFICE.

WILLIAM FONGER, OF CHICAGO, ILLINOIS, ASSIGNOR TO FONGER FENDER COMPANY, OF CHICAGO, ILLINOIS, A CORPORATION OF SOUTH DAKOTA.

FENDER FOR AUTOMOBILES, &c.

1,253,021.

Specification of Letters Patent.

Patented Jan. 8, 1918.

Application filed February 20, 1917. Serial No. 149,834.

To all whom it may concern:

Be it known that I, WILLIAM FONGER, a citizen of the United States, residing at Chicago, in the county of Cook and State of Illinois, have invented new and useful Improvements in Fenders for Automobiles, &c., of which the following is a specification.

This invention relates particularly to fenders for automobiles, or the like; and the 10 primary object is to provide an improved device of the character indicated which can be readily applied to an automobile, or auto-truck, which is of staunch construction, and which operates in an improved manner.

15 The invention is illustrated in its preferred embodiment in the accompanying drawings, in which—

Figure 1 represents a broken elevational view of an automobile equipped with my improved fender; Fig. 2, a broken view of the worm-shaft employed for raising and lowering the lower frame of the fender; Fig. 3, a broken front elevational view of the improved fender; Fig. 4, a broken side elevational view illustrating the manner in which the fender is mounted on the front end of the frame of the chassis; Fig. 5, a broken sectional view showing the trip-device for the automatically reversible fender, proper; Fig. 6, a sectional view of the hook, or latch-member, of the trip; Fig. 7, a broken vertical sectional view, showing the manner in which the fender, proper, is locked in the operative, or pick-up, position, the section 25 being taken at the position indicated by the section line 7 on Fig. 3; Fig. 8, a broken rear elevational view of the fender, proper, in the lowered or operative position, the view being taken as indicated at line 8 of Fig. 7; Fig. 9, a broken horizontal sectional view taken as indicated at line 9 of Fig. 3; Fig. 10, a broken vertical sectional view, taken as indicated at line 10 of Fig. 3; Fig. 11, a broken vertical sectional view, taken as indicated at line 11 of Fig. 9 and Fig. 12, a broken plan view showing the manner in which the automatically reversible fender, proper, is mounted on the lower frame of the device.

50 In the construction illustrated, A represents the frame of an automobile chassis, the

front ends of the side members of which are equipped with upper brace-members A' and lower brace-members A²; B, B, a pair of goose-neck supports, whose curved upper 55 ends are secured, by bolts 1, to the front ends of the upper braces A'; B', B', castings, or fittings, secured to or rigidly carried by the lower ends of the depending vertical portions 2 of the goose-neck members 60 B, the fittings B' being provided at their rear sides with lugs 3, to which the front ends of the lower braces A² are secured, by bolts 4; C, an upper fender-member, or buffer, which comprises a rectangular frame 65 C' equipped with a suitable covering, or lattice-work C², the lower member of the frame C' being provided with rearwardly offset bearing-portions 5 supported in recesses, or sockets, 5^a, with which the upper portions of 70 the lugs 3 are provided; D, a lower fender-frame having a rear member 6 journaled in the lower ends of the castings B', curved arms 6^a carried by the member 6, a front cross-member 6^b carried by the arms 6^a, and 75 forward extensions 6^c equipped with in-turned trunnions 6^d; E, an automatically reversible fender, proper, supported by the trunnions 6^d; F, a device for effecting automatic reversal of the member E; and G, 80 mechanism for swinging the frame D in the bearings with which the lower ends of the fittings B' are provided.

The members of the frame A which carry the braces A' and A² may be the usual longitudinal channel members of the chassis frame.

The fittings B', which are carried by the depending vertical member 2 of the goose-necks B, are equipped on their outer sides 90 with lugs 7, which are fitted with bolts 8, which afford stops, limiting the downward swing of the frame D, as will be understood from Fig. 6.

The frame C', as has been indicated, is 95 pivotally supported in the bearings 6 of the fittings B'. The frame may be composed of a pipe bent to rectangular form and having its lower member interrupted, the interruptions being bridged by rearwardly offset 100 rods which form the bearing-members 5, as will be understood from Figs. 3 and 9. The

frame C' is therefore capable of tilting on the pivotal portions 5. The upper and lower members of the frame C' are connected by vertical cross-bars 9, which are disposed in the rear of the upper or curved portions of the goose-necks B; and the members 9 are fitted on their front sides with loops or bent straps, 9a, which freely embrace the upper portions of the goose-necks B, thus 10 permitting limited swinging movement of the frame C' about the bearings 5a. The lattice-work C' is bowed forwardly from the plane of the frame C', so that the freedom of movement of the frame will not be interfered with.

Connected with and depending from the upper member of the frame C' are counter-balancing springs 10, whose lower ends are connected, by chains 10a, with an intermediate portion of the lower frame D, the lower ends of the chains 10a being attached to curved bars 11, with which the frame D is equipped, the rear ends of said bars 11 being extended rearwardly above the pivotal member 6 of the frame D, so as to contact with the stop-bolts 8, in the position shown in Fig. 4. The bolts 8 are fitted with washers, and may be adjusted with relation to the lugs 7, by which they are carried, so that the bolts afford, in effect, adjustable stops.

The frame D is covered with a suitable lattice-work 12. The springs 10 serve as counterbalancing springs for the frame D, thus enabling the frame D to be adjusted 35 with great facility by means of the mechanism G. It will be noted, also, that the springs 10 tend to throw the upper portion of the member C forward, so that the vertical bars 9 rest normally against the rear surfaces of the curved portions of the goose-necks B. Thus, the member C is held yieldingly in a given angular relation with respect to the frame D, when the device is in the position shown in Fig. 4.

45 The automatically reversible fender, proper, E comprises an elongated body of somewhat oval form, whose ends are provided with eccentric bearings 13 mounted on the trunnions 6a. The rear corners of the member E rest upon coil springs 14, which are diagonally disposed and which have their ends connected with the members 6b and the arms 6c of the frame D, as shown in Fig. 12. The springs 14 will yield to permit the 55 member E to swing downwardly, when the automatic reversing action occurs.

The member E is adapted to be forcibly swung rearwardly and downwardly, from the position shown in Fig. 4 to the position 60 shown in Fig. 7, by means of the mechanism F. The mechanism F comprises a hook, or trip-member, 15, which normally engages the cross-member 6a, as shown in Fig. 5, said hook being provided with a trip-arm, or 65 nose, 15a, adapted to be struck by the rear

portion of the member E when the member E is swung rearwardly, as occurs when a body is encountered; a chain 16 connected with the shank of the hook 15 and having an extension 16a which passes through a 70 perforation 16b (Fig. 6) in the trip-arm of the hook, and thence about the body E, the extremity being secured to the body at the point 16c; a pulley 17 mounted on the rear portion of a bar 17a beneath which the hook, or trip-member, 15 is adapted to slide, about which pulley the chain 16 passes; and a heavy coil spring 18 connected with the chain and secured to one of the goose-necks B. When the member E is swung rearwardly and downwardly, as occurs when a body is encountered, the first movement depresses the trip 15, whereupon the spring 18 operates to forcibly reverse the body E. Because of the eccentric mounting of the member E, said member dips downwardly in the reversing action, so as to approach the ground more closely and insure the picking up of the body encountered. If desired, the member E may be swung rearwardly 80 to work the trip, by means of a flexible connection 19 (Fig. 3), which may pass to a convenient location near the steering-wheel of the machine. The springs 14 serve to prevent accidental operation of the trip, due to jarring actions of ordinary traffic. When, however, the fender, proper, E, is encountered by a body, the springs 14 yield to permit the trip to be operated.

The member E is equipped at an intermediate portion with a socket 20 adapted to be engaged by a spring-projected bolt 21, which moves in a guide 22, with which the front cross-member 6b is equipped (Figs. 7 and 12). The socket 20 is formed in that 100 edge of the member E which is normally presented forwardly. It is formed in a metal member 20a, with which the fender E is equipped, said member 20a being provided with a sloping guide-slot 20b, which 110 operates to retract the bolt 21 against the force of its spring when the member E is reversed, the head of the bolt 21 finally entering the socket 20 and positively locking the member E against swinging in either direction about the trunnions 6a. Before the member E can be re-set in the position shown in Fig. 4, the bolt 21 must be retracted by means of a knob 21a to permit the member E to be rotated about the trunnions 6a. 115

The mechanism G, by means of which the frame D may be swung from the position shown in Fig. 4 to the position shown in Fig. 1, or vice versa, preferably comprises a worm-shaft 23 equipped at its upper end 120 with a hand-wheel 23a provided with a knob 23b; a worm 24 secured to the lower end of the shaft 23; a worm-wheel 25 fixedly secured to the rear member 6 of the frame D; and a gear-casing 26 journaled on the 130

tabular member 6. The gear-casing 26 comprises upper and lower sections which are bolted together. The gear-casing is held in the position illustrated in Fig. 10 by means of an arm 27 which projects from the plate 27^a, which is secured to the gear-casing by the bolts which connect the two halves of the gear-casing, as will be understood from Figs. 3 and 10. The rear end of the arm 27 is held loosely in the loop of a bracket 28 secured to one of the braces A². The operating shaft 23 of the worm 24 inclines rearwardly and upwardly, and the hand-wheel 23^a is located within convenient reach of the operator. It may be located near the steering wheel of the machine. The lower end of the shaft 23 is journaled in the upper portion of the gear-casing 26, being held against longitudinal movement by a collar 29 and a bearing 30. Owing to the fact that the frame D and the automatically reversible fender, proper, E are substantially counter-balanced by the springs 10, it will be understood that the frame D may be easily raised by spinning the hand-wheel 23^a through the medium of a knob 23^b. The frame may be lowered by the reverse operation. The frame D will stay in the position in which it is set, owing to the interlocking action of the worm on the worm-wheel. However, when the frame D is in the lowered position, it is desirable to provide against undue strain upon the worm mechanism; hence the stops 8 are adjusted to limit the downward swing of the frame D through contact with the rearward extensions of the bars 11. This will be understood from Fig. 4.

In the use of the device, the parts normally occupy the position shown in Fig. 4. If, while the automobile is being driven, the member E encounters a body, it will be swung rearwardly and downwardly, working the trip 15, whereupon the operating spring serves to forcibly reverse the member E. In this action, the bolt 21 is automatically retracted and then entered in the socket 20, thereby locking the member E against swinging in either direction about the trunnions 6^a. In case the driver notes in time the danger of an accident, he may, by pulling the cord 19, manually trip the member 15, thereby enabling the spring 18 to reverse the member E. In case an accident cannot be averted, the shock of a body encountering the upper member C of the fender will be broken by the springs 10, which yield to permit the member C to swing rearwardly about the offset bearing 5 or pivot-portions 5.

It may be added that the purpose of allowing a certain play of the arm 27 in the bracket or loop 28 is to permit a limited oscillation of the gear-casing 26. Normally, the weight of the lower fender-frame holds

the arm 27 against the upper wall of the loop 28. In case the unevenness of the road-bed causes the front end of the lower fender-frame to raise, however, the gear-casing (in which the shaft 23 is journaled) will swing to compensate for the enforced swing of the lower fender-frame, thus avoiding breakage.

The construction described is simple, durable, easily operated, and effective for its purpose.

The foregoing detailed description has been given for clearness of understanding only, and no unnecessary limitations should be understood therefrom, but the appended claims should be construed as broadly as permissible, in view of the prior art.

What I regard as new, and desire to secure by Letters Patent, is;

1. In a device of the character set forth, the combination with supporting members, of an upper fender-frame having its lower portion pivotally supported thereon, a lower fender-frame having its rear portion pivotally connected with said supporting members, and a counter-balancing spring connecting said lower fender-frame with the upper portion of said upper fender-frame.

2. In a device of the character set forth, the combination with supporting members, of an upper fender-frame having its lower portion pivotally supported by said members, a lower fender-frame having its rear portion pivotally connected with said supporting members, counter-balancing springs connecting said fender-frames, and mechanism for swinging said lower fender-frame about its pivot, including an actuating shaft equipped with a hand-wheel.

3. In a device of the character set forth, the combination with supporting members, of an upper fender-frame carried thereby, a lower fender-frame pivotally mounted at its rear end, and worm-gear mechanism for raising and lowering the lower fender-frame, having a worm-wheel secured to the pivotal portion of said lower fender-frame, and having, also, an actuating shaft equipped with a handle.

4. In a device of the character set forth, the combination with supporting members, of an upper fender-frame carried thereby, a lower fender-frame having its rear end pivotally mounted on the lower portion of said upper frame, a worm-wheel secured to the pivotal portion of the lower fender-frame, and a rearwardly and upwardly inclined actuating shaft equipped at its lower end with a worm engaging said worm-wheel and equipped at its upper end with a member for turning the shaft.

5. In a device of the character set forth, the combination with supporting members, of a lower fender-frame having its rear portion pivotally mounted, a gear-casing

- 5 journalled on the pivotal portion of said lower fender-frame, means for holding said gear-casing in position, a worm-wheel secured to the pivotal portion of said lower fender-frame, and an actuating shaft equipped with a worm engaging said worm-wheel and equipped also with means for rotating the shaft.
6. In a device of the character set forth, 10 the combination with supporting members, an upper fender-frame mounted thereon, a lower fender-frame having a rear member pivotally mounted in said supporting members, a gear-casing journalled on said rear member, a stationary bracket securing said gear-casing in position, a worm-wheel in said gear-casing secured to said rear member, an inclined actuating shaft extending into said gear-casing and equipped with a 15 worm engaging said worm-wheel, and means on the upper end of said shaft for rotating the shaft.
7. In an actuating device of the character set forth, the combination of supporting 20 members having vertical portions equipped at their lower ends with fittings, means for mounting said members on the front portion of an automobile frame, an upper fender-frame having its lower portion pivotally mounted on said fittings, a lower fender-frame having a rear member journalled in said fittings, a counter-balancing spring connecting the upper fender-frame with said lower fender-frame, a gear secured to the 25 rear member of said lower fender-frame, and actuating means for said gear, including a shaft equipped with a hand-wheel.
8. In a device of the character set forth, 30 the combination of a pair of supporting members of goose-neck form having depending vertical portions equipped with fittings, bracket-members connected with the upper portions of said members, bracket-members connected with said fittings, an upper fender-frame mounted on said supporting members, a lower fender-frame having a rear member journalled in said fittings, a gear secured to the 35 rear member of said lower fender-frame, and actuating means for said gear, including a shaft equipped with a hand-wheel.
9. In a device of the character set forth, 40 the combination of supporting members equipped at their lower portions with fittings, means for mounting said supporting members on the front end of an automobile frame, an upper fender-frame having its lower portion pivotally mounted in said fittings, said frame equipped with means adapted to engage the upper portions of said 45 supporting members and limiting the swinging movement of said fender-frame, a lower fender-frame having a rear member pivotally mounted in said fittings and equipped with a gear-member, actuating means, including a shaft, for turning said gear-mem- 50 ber, and counterbalancing springs connecting the upper portion of said upper fender-frame with an intermediate portion of said lower fender-frame.
10. In a device of the character set forth, 70 the combination of supporting members equipped at their lower ends with fittings, an upper fender-frame mounted on said supporting members, a lower fender-frame having a rear member journalled in said fittings 75 and equipped with a gear, means for manually actuating said gear, and co-acting stops carried by said fittings and the rear portion of said lower fender-frame, said stops limiting the downward swing of the lower fender-frame.
11. In a device of the character set forth, 80 the combination of a pair of goose-neck supports having depending vertical portions equipped at their lower ends with fittings, 85 brace-members connected with the upper curved extremities of said goose-necks, brace-members connected with said fittings, an upper fender-frame having its lower portion pivotally mounted on said fittings, a lower fender-frame having its rear member pivotally journalled in said fittings, and a counter-balancing spring connecting the upper portion of said upper fender-frame with an intermediate portion of said lower fender-frame.
12. In a device of the character set forth, 90 the combination of supporting members, an upper fender-frame having rearwardly offset pivot-positions at its lower edge mounted 100 in the lower portions of said supporting members, a lower fender-frame having its rear portion pivotally connected with said supporting members, and a counter-balancing spring connecting the upper fender-frame with an intermediate portion of said 105 lower fender-frame.
13. In a device of the character set forth, the combination with a fender-frame, of a normally elevated, eccentrically mounted 110 fender adapted to swing rearwardly and downwardly when the fender encounters a body, and diagonally-disposed coil-springs carried by said fender-frame upon which the rear corners of said fender bear, said springs 115 adapted to move out of the way when the said fender is forcibly reversed.
14. In a device of the character set forth, the combination with a fender-frame, of a normally elevated, eccentrically mounted 120 fender adapted to turn rearwardly and downwardly, coil-springs stretched on said frame and yieldingly supporting said fender at the rear corners thereof, and reversing mechanism for said fender, including an 125 actuating spring, a flexible connection between said actuating spring and said fender, and a trip-device normally restraining said spring from action.
15. In a device of the character set forth, 130

the combination with a fender-frame, of a rearwardly and downwardly reversible fender pivotally mounted in the front portion of said frame and equipped at its normally front edge with a socket, reversing mechanism for said fender, including an actuating spring, a trip-device and a flexible

connection between said spring and said fender, and a spring-projected bolt carried by said frame and adapted to enter said 10 socket and positively lock the fender against turning in either direction after reversal.

WILLIAM FONGER.
